UNITED STATES PATENT OFFICE.

WALTER G. DOWS, OF DORCHESTER, MASSACHUSETTS.

PIPE FITTING.

Application filed March 11, 1925. Serial No. 14,729.

This invention relates to pipe fittings for connecting radiators to a riser.

The radiators of a building are commonly connected to vertical pipes extending upwardly through the different floors of a building and which are known as "risers". These vertical pipes or risers commonly extend from the basement to the top floor of a building, and when the building is tall it is necessary to provide means for taking care of the change in length of the risers due to expansion and contraction.

In connecting a radiator to a riser it often occurs that the connection receiving opening of the radiator is either too high or too low to be readily connected to the fitting of the riser; furthermore some radiators are wider than others, that is they project outwardly from a wall of the room further than others, and this may increase the difficulty of securing a radiator to a riser fitting.

Having the above matters in mind the present invention relates to a fitting for connecting a radiator to a riser while it serves also to take care of the expansion and contraction of the riser, and the construction is such that the fitting, while connected to the riser, may be raised and lowered to facilitate connecting the fitting to a radiator, and it may also be rotated thru a sufficient angle to bring a laterally extending neck of the fitting into alignment with the portion of the radiator to which it is to be secured.

The above and other features of the invention will be best understood from the following description, when read in connection with the drawings which illustrate a good, practical form of the invention.

In the drawings:—

Fig. 1 is a perspective view showing a portion of a room having a radiator therein which is connected to its riser in accordance with the present invention.

Fig. 2 is an enlarged vertical sectional view thru the fitting of Fig. 1.

Fig. 3 is a perspective view of a sleeve which may be secured to a pipe of the riser to extend into the fitting; and

Fig. 4 is a fragmentary perspective view of the upper portion of the fitting of Fig. 2.

Referring to the drawings, 10 is a riser that may extend from the basement of a building upwardly thru the different floors to supply a heating fluid to one or more radiators upon each floor. The riser 10 is usually positioned near one of the walls 11 of

the room and supplies the radiator 12 with a heating fluid. In some heating systems the radiators are connected to both supply and return risers, while in other systems a single riser serves to conduct the heating fluid to and from the radiator, and in the drawings the radiator is shown as connected to only one riser, but the fitting of the present invention may be used to connect a radiator to either a supply or return riser.

As stated, when the riser 10 extends upwardly thru several or a number of floors, it is necessary to provide means for taking care of the change in length of the riser, due to contraction and expansion. To this end, in accordance with the present invention, the fitting comprises a hollow casing 13 having a relatively long internal bore 14 into which an end of a pipe of the riser may extend a substantial distance.

A stuffing box is provided for preventing fluid from escaping from the upper end of the casing 13 around the outer wall of the riser pipe 10 extending therein, and this stuffing box serves also to permit relative movement between the casing and pipe 10. The stuffing box may be variously constructed, and in the construction shown the casing 13 is provided with an inwardly extending annular flange 15, the inner bore of which is shown as somewhat larger than the outer diameter of the pipe 10. A ring 16 is therefore provided to rest upon the annular flange 15 and form a seat for the packing 17 which may be forced downwardly against its seat by the gland nut 18.

This construction serves to permit the casing 13 to be raised and lowered relatively to the pipe 10 after the parts have been assembled, and serves also to take care of the contraction and expansion of the pipe 10. It has a still further advantage in that it permits any pipe of a riser to be removed or inserted without disassembling the entire riser. This is due to the fact that the bore 14 of the casing is sufficiently long to permit the pipe 10 to be lowered into the bore far enough to allow its threaded upper end to be screwed into a threaded socket of a similar casing 13 at the upper end of the pipe 10, and supported upon the floor above. The inner bore of the gland nut 18 preferably fits the pipe 10 somewhat loosely to facilitate the removal and installation of a pipe section of the riser in the manner just pointed out.

The casing 13 is provided with a laterally extending neck 19 and in the construction shown this neck has an upturned portion 20 which is externally threaded. It often happens that the connection receiving opening 21 of a radiator is either too high or too low to be readily connected to the riser fitting. To overcome this difficulty the casing 13 is constructed so that it may be raised or lowered to facilitate the connection of the threaded end 20 with the radiator thru the valve 22 thereof, and means is provided for supporting the casing 13 in different positions of adjustment. To this end the casing 13 is externally threaded as at 23 and is adapted to receive a correspondingly threaded nut or sleeve 24. This sleeve is provided with a laterally extending flange 25 which rests on the floor 26 of the room. The nut or sleeve 24 preferably is constructed so that it may be adjusted a substantial distance lengthwise of the casing 13, to support the casing in various positions of vertical adjustment relatively to the floor. After the sleeve 24 has been adjusted to the desired position it may be secured in this position by one or more set screws 27 carried by the sleeve, and the sleeve may be secured to the floor 26 by screws 28 extending thru the flange 25 into the floor. The sleeve 24 has an annular portion 29 which fits a hole in the floor and the sleeve is preferably provided with a shoulder 30 which may rest upon the boards of the lower floor to support the fitting in its proper position until the boards of the upper floor are laid. The lower end of the sleeve 24 extends into the hole in the lower floor and serves to center the sleeve therein.

The lower end of the casing 13 is preferably provided with a threaded socket 31 adapted to receive the threaded upper end of a pipe 32 of the riser, the arrangement being such that one end of a pipe of a riser (in the construction shown, the upper end) is rigidly secured to the casing 13, while the lower end of this same pipe extends slidably into a second casing 13 thru a stuffing box such as shown and described. This construction permits the casing 13 and the pipe 32 rigidly secured thereto to be raised and lowered as a unit without disturbing the operation of the riser.

Some radiators are wider than others; that is, they may extend outwardly from a wall 11 of the room further than others so that the connection receiving opening 21 of some radiators may be spaced further from the wall 11 than others. In order that the neck 19 may be readily connected to radiators of different widths, the neck is made relatively long, as shown, and the casing 13 may be rotated to swing the neck into alignment with the valve 22 or other connection with which its threaded end 20 is to be secured.

In some cases it may be desirable to provide the pipe of the riser 10 which is slidably secured to the fitting with a sleeve 33 which may extend into the casing 13. This may be desirable where a smoother external surface is desired than that afforded by the pipes of the riser, and makes it easier to remove a section of the riser. When the sleeve 33 is employed the pipe 10 will not extend into the fitting, but the sleeve will be connected by threads to the lower end of the pipe so that the sleeve will extend thru the stuffing box into the fitting. The sleeve 33 is shown as provided with a collar 34 at its lower end; this collar is preferably permanently secured thereto and is provided to prevent the sleeve from being accidentally pulled out of the stuffing box before the fitting has been installed in the heating system, and the bore of the annular flange 15, as above stated, is made somewhat larger than the diameter of the pipe 10 to permit the sleeve 33 and collar 34 to be inserted within the bore 14 of the casing.

It may be desirable to provide a watertight joint between the fitting supporting base plate and the floor, so that water upon the floor due to radiator leakage, washing the floor, or, in case of a fire, will not pass downwardly around the fitting. This is readily accomplished by placing graphite paste or the like on the threads within the collar 24 of the base plate so that water will not pass downwardly between the cooperating threads, and a gasket 35 confined between the floor and under face of the flange 25 will prevent water from entering at this point. This construction is particularly desirable in rooms provided with tile or other waterproof floors, as the floor may be made absolutely tight.

From the foregoing description, it will be apparent that after the fitting has been secured to a riser, it may be raised and lowered as desired to facilitate the connection of the fitting to a radiator, and that the fitting may be supported from the floor in its different positions of adjustment by the base plate or floor flange formed by the nut or collar 24. It will also be seen that this fitting takes care of the change in length of the riser, due to expansion and contraction, and that the fitting may be readily rotated about a vertical axis thru a sufficient angle to bring the outer end of the neck 19 into alignment with the radiator connection to which it is to be secured.

What is claimed is:—

1. A pipe fitting for connecting a radiator to a riser, comprising in combination, a hollow fluid-tight casing adapted to form a connection between two aligned pipes of a riser, a neck extending laterally from the casing and having an upwardly extending end for connection to a radiator, means

forming a sliding connection between the casing and one of said pipes to permit the casing to be adjusted vertically relatively to the last mentioned pipe while rigidly secured to the other pipe, and a supporting sleeve threaded upon the casing for adjustment lengthwise of the casing and provided with a laterally extending flange adapted to rest upon the floor of a building to support the casing.

2. A pipe fitting for connecting a radiator to a riser, comprising in combination, a hollow fluid-tight casing adapted to form a connection between two aligned pipes of a riser, a neck extending laterally from the casing and having an upturned end portion for attachment to a radiator, means for rigidly securing one pipe to the lower end of the casing to suspend the same from the casing so that the pipe may be raised and lowered with the casing, means forming a sliding connection between the other pipe and the casing to permit the casing to be adjusted vertically relatively to the last mentioned pipe, and a supporting sleeve threaded upon the casing for adjustment lengthwise thereof and provided with a flange portion adapted to rest on the floor of the building to support the casing in different positions of adjustment and so that the casing may be rotated about the riser as an axis to align the outer end of said neck with the radiator connection.

3. A pipe fitting for connecting a radiator to a riser, comprising in combination, a hollow fluid-tight casing adapted to form a connection between two aligned pipes of a riser, a neck extending laterally from the casing and having an upturned end for attachment to a radiator, means for rigidly securing one pipe to the casing to be raised and lowered with the casing, means forming a sliding connection between the other pipe and the casing to permit the casing to be adjusted vertically relatively to the last mentioned pipe, and a supporting sleeve threaded upon the casing for adjustment lengthwise thereof and provided with a flange portion adapted to rest on the floor of a building to support the casing in different positions of adjustment, and means for locking the sleeve to the casing in its adjusted position.

flange portion adapted to rest on the floor of a building to support the casing in different positions of adjustment.

4. A pipe fitting for connecting a radiator to a riser, comprising in combination, a hollow fluid-tight casing adapted to form a connection between two aligned pipes of a riser, a neck extending laterally from the casing and having an upturned end for attachment to a radiator, means for rigidly securing one pipe to the casing to be raised and lowered with the casing, means forming a sliding connection between the other pipe and the casing to permit the casing to be adjusted vertically relatively to the last mentioned pipe, a supporting sleeve threaded upon the casing for adjustment lengthwise thereof and provided with a flange portion adapted to rest on the floor of a building to support the casing in different positions of adjustment, and means for locking the sleeve to the casing in its adjusted position.

5. A pipe fitting for connecting a radiator to a riser, comprising in combination, a hollow fluid-tight casing adapted to form a connection between two aligned pipes of a riser, a neck extending laterally from the casing and having an upturned end for attachment to a radiator, means for rigidly securing one pipe to the casing to be raised and lowered with the casing, means forming a sliding connection between the other pipe and the casing to permit the casing to be adjusted vertically relatively to the last mentioned pipe, a supporting sleeve threaded upon the casing for adjustment lengthwise thereof and provided with a flange portion adapted to rest on the floor of a building to support the casing in different positions of adjustment, and a gasket confined between said flange portion and floor to prevent water upon the floor from passing downwardly through a riser opening in the floor.

In testimony whereof, I have signed my name to this specification.
